UNITED STATES PATENT OFFICE.

FREDERICK E. HILLIARD, OF BROOKLYN, NEW YORK, ASSIGNOR TO
LIPPMAN TANNENBAUM, OF NEW YORK, N. Y.

APPARATUS FOR GRINDING AND POLISHING GEMS.

SPECIFICATION forming part of Letters Patent No. 701,879, dated June 10, 1902.

Application filed December 26, 1901. Serial No. 87,220. (No model.)

To all whom it may concern:

Be it known that I, FREDERICK E. HILLIARD, a citizen of the United States, residing at No. 302 Livingston street, in the borough of Brooklyn, county of Kings, city and State of New York, have invented certain new and useful Improvements in Apparatus for Grinding and Polishing Gems, of which the following description and accompanying drawings constitute a specification.

My improvement relates to machines for manipulating precious stones while undergoing the process of grinding and polishing.

It consists in an improved supporting-arm capable of ready, precise, and positive adjustments with relation both to the work-table or supporting-frame and to the lap or polishing wheel usually employed by lapidaries.

My invention further and particularly relates to an improved mechanism for regulating and controlling the dop or stick for holding the gem being ground or polished, consisting of an improved dop-holder, by means of which the gem may be presented to the lap through a wider range of angles and positions and with greater precision, accuracy, and rigidity than by any means now known in the art, thus enabling the lapidary to produce a cutting of any predetermined pattern, the facets of the gems so cut being disposed with utmost regularity.

My invention further consists in certain structural advantages permitting increased range and facility of operation and observation, hereinafter more particularly described.

In the drawings forming part of this specification, Figure 1 illustrates in side elevation, partially sectional, the supporting-arm secured to the work-table and adjusted to the lap, the dop, spindle, and adjustable holder being indicated in dotted outline. Fig. 2 illustrates in section the cylindrical shoulder borne by the vertical screw member of the supporting-arm and against which the dop-holder is pressed by the lapidary. Fig. 3 is a side view, and Fig. 4 is a top view, of the part illustrated in Fig. 2. Fig. 5 shows the dop, its holder, and adjusting mechanism, principally in sec-

tion. Fig. 6 shows the same parts on a plane at right angles to Fig. 5 with the casing partially broken away and the supporting-socket in section. Fig. 7 illustrates the dop-spindle carrying the rigidly-mounted toothed guide-wheels shown in Figs. 10 and 13 in detail, Fig. 10 illustrating a guide-wheel of sixteen teeth, and Fig. 13 illustrating a guide-wheel of twenty teeth. Fig. 8 is a view of the end of the dop-holder shown adjacently in Fig. 5 and illustrates the concaved socket terminating the upper end of the tool adapted to engage with a cylindrical shoulder of a guide-block and pierced to allow the introduction of the screw-bearing. Fig. 11 is a view of the end of the dop-holder shown adjacently in Fig. 5 and illustrates the screw-cap closing the lower end of the tool and bearing a scale registering with a pointer borne on the spindle. Figs. 9 and 12 are vertical sections through the dop-spindle and holder, as shown in Fig. 6, and at right angles thereto, illustrating, respectively, the two positions of the toothed clamp, Fig. 9 showing it disengaged from and Fig. 12 showing it in engagement with its corresponding guide wheel or disk.

Similar reference characters indicate corresponding parts throughout these several figures, as follows:

1 is the bench or table; 2, the revolving lap; 3, the supporting-post for the bed of the frame; 4, the clamp, permitting the raising and lowering of the post; 5, the frame-bed, upon which rests the supporting-arm 6; 7, the clamp for permitting the forward or backward movement of the frame; 8, a screw-post revolvably set at its base in the frame-bed and at its top in the supporting-arm; 9, a gnarled head for turning the screw-post, permitting the block 10 to travel thereon; 11, a screw-clamp for setting the block 10 at a desired height. The block 10 carries the pointer 12, indicating its height on the scale 13, borne by the supporting-arm 6.

14 is a cylindrical shoulder, against which butts the socket 15 of the dop-holder 16.

17 is the gem-stick holder on the spindle extension.

18 is a set-screw permitting the holder to be turned to any desired angle of inclination to the lap.

19 is the dop-spindle, bearing the toothed 5 guide-disks 20.

21 represents slotted latches sliding under the screws 22.

23 represents springs pressing against the toothed clamps 24 and held by the screws 25.

26 is an annulus to tighten the split holder 10 27 upon the dop or stick for holding the gem. (Not shown.)

28 represents the knobbed pins for releasing the clamps from engagement with the 15 toothed guides 20.

29 is a pointer registering with the scale 30, indicating the set position of the spindle.

The scale 30 is shown as upon the bottom 20 of the tool; but in my preferred form of construction this scale is borne on the side of a revoluble cap surmounting 31, which is the screw-cap closing the lower end of the holder to exclude dust and forming the bearing of the lower end of the dop-spindle. In the preferred 25 construction the pointer is fixedly mounted on the side of the tool.

The holder is cylindrical in form, being extended at one end to form a bearing-socket, pierced to permit an adjustable screw-bear-30 ing firmly to center the spindle-shaft, whose outer end sets in a recess in the incasing holder and whose lower end is centered by a bearing in the screw-cap closing the lower end of the holder, said cap being bored to 35 permit the lower end of the spindle to project from the holder, such extension being screw-threaded to receive the dop-holder proper, which is interiorly threaded to engage firmly with such spindle and whose 40 lower end is split to receive the gem-stick, which is retained therein by the screw-threaded annulus engaging with the thread on the exterior of said dop-holder. The spindle proper freely revolves in its bearings and has 45 rigidly fixed to it, or preferably integral therewith, a number of peripherally-toothed guide-disks. The drawings show eight, the four upper disks having sixteen teeth each, while the four lower each have twenty. These 50 disks are so disposed as to permit the engagement of any single disk by the toothed stop controlling it upon the pulling out of the sliding latch on the exterior of the holder corresponding to the disk desired, such latch normally holding its stop out of engagement. The spindle is thus set by the interlocking of the teeth of any stop with the teeth of its corresponding disk, as upon releasing the stop 55 from its latch it engages with its disk by 60 spring-pressure and is so held until disengaged by pressing the corresponding button and by sliding the latch forward to retain it in its normal position of non-engagement. These disks have their teeth so disposed as to 65 permit the gem to be girdled, in the example

selected, with sixteen facets. Each disk serves as it is rotated tooth by tooth to present a fresh part of the gem's surface, and as a facet is cut the spindle is rotated another tooth and a new facet is presented until the 70 disk has completed step by step its revolution. The disk is then held in engagement until the second disk is ready to control the spindle, being held by its stop meanwhile, and the cutting then proceeds, the new disk similarly being revolved step by step and the spindle turning correspondingly, presenting, for example, the angles formed by the facets of the primary girdle. The revolution of the second disk thus produces a girdle of thirty-two facets. 80 The angles formed by these new facets in turn may be ground off by the use of the third and fourth disks, thus again doubling the number of facets. The disposition of the peripheral teeth is seen to be simply a matter of mathematical calculation. In the example illustrated and just described there are two sets of disks—four to each set, as stated. The first set has four disks of sixteen teeth each, and the second set has four disks of twenty teeth 90 each, the first set being adapted to produce the several patterns of cutting known as the "brilliant" cuts. The teeth are disposed at equally-distant intervals about the periphery, the spaces between them equaling their width 95 in all cases. In disk *a* the sixteen teeth are the standard to which the location of the teeth of the other disks of its set are related. The teeth on disk *b* are opposite the intervals between the teeth on disk *a*. Disk *c* has its teeth 100 so set that the angles formed by the facets resulting from the cutting with disks *a* and *b* are presented as the spindle is revolved. As but sixteen teeth are shown on disk *c*, but sixteen cuttings may be made by it. As this is 105 but half the number of angles resultant from the cuttings with disks *a* and *b*, a fourth disk is needed to cut the remaining sixteen facet-angles, and so to complete the sixty-four facets. It is obvious that disk *c* might have 110 thirty-two teeth and the entire cutting of sixty-four facets be completed with the third disk; but I find better results are obtained by dividing the regulation between two disks, as the limit of mechanical perfection attainable in tools for work of this fineness and 115 which are subject to severe strain by reason of the hardness of the gems seems to be reached when more than twenty fixed positions are sought to be given the spindle by a 120 controllable hand-tool, a greater number of teeth than twenty resulting in a sacrifice of rigidity.

The dop-holder is shown in the drawings in full size and is adapted to be held conveniently in the hand, affording ease and certainty in manipulation. By means of my tool the lapidary may execute with exactness all the usual styles of cuttings of gems, brilliant, rose, and table or trap, with their variations, 130

as half, full, split or double brilliant, and can modify these cuttings or produce manifold new cuttings, and in particular can cut to best advantage gems of irregular outline, 5 such as pear shapes, hearts, and marquise.

In cutting a brilliant, for example, it is necessary with the prior forms of mechanical guides to remove the gem-holding stick from the holder in order to girdle the stone with 10 more than thirty-two facets; but with my tool the whole cutting may proceed without removal of the gem by a simple series of adjustments up to a girdle of eighty facets, the limitation of that form of my invention shown.

15 Having thus described my invention, what I desire to claim is—

1. In a machine for cutting and polishing gems, the combination of a standard; means for adjusting same vertically and horizontally, a screwed shaft-support from and revolvably mounted in said standard with means for revolving said shaft, a screw-threaded block arranged to travel on said shaft, means for setting said block rigidly at any point on 20 said shaft, means for registering the elevation of said block, a shoulder on said block and

means for adjusting the angle of inclination of the said shoulder, substantially as shown and described.

2. A dop-holder having a cylindrical casing, 30 a spindle revolvably mounted therein, a plurality of toothed disks centered on said spindle, an equal number of toothed stops set transversely through said casing, a corresponding series of springs on said casing engaging with 35 said stops and tending to engage them with said disks, a corresponding series of latches on said casing holding said stops normally out of engagement and means for releasing the stops from engagement, substantially as 40 shown and described.

3. In a dop-holder, the combination of a cylindrical casing, a spindle revolvably mounted therein, a contained means for positively locking said spindle at any desired point of 45 rotation, with means for measurably indicating such degree of rotation, as and for the purposes set forth.

FREDERICK E. HILLIARD.
